UNITED STATES PATENT OFFICE.

THOMAS C. BOOTH, OF NEW YORK, N. Y.

ATTACHMENT FOR COLLAPSIBLE TUBES.

1,148,284.

Specification of Letters Patent. Patented July 27, 1915.

Application filed April 30, 1914. Serial No. 835,501.

To all whom it may concern:

Be it known that I, THOMAS C. BOOTH, a citizen of the United States of America, and resident of the borough of Manhattan, in the city of New York, county and State of New York, have invented certain new and useful Improvements in Attachments for Collapsible Tubes, of which the following is a specification.

10 This invention relates to collapsible tubes intended for tooth-pastes, paints, cold creams, vaseline, cement and the like, and more particularly to attachments therefor, the object of the invention being to provide 15 an improved attachment for collapsible tubes the use of which insures the regular and uniform expulsion of the contents of the collapsible tube during its use, and at the same time affords improved means intended to be used for advertising and displaying purposes.

A further object of the invention is to provide such an attachment which operates to prevent the mashing or undesired collapsing of the tube, as happens by the handling of the tubes either in transit or when on display, by means of which unequal indentations the use of the tube is seriously affected.

My invention is shown in the accompanying drawing and will be more fully described hereinafter and finally pointed out in the claim.

In the accompanying drawing, Figure 1 is a front-view of my improved attachment applied to a collapsible tube, Fig. 2 is a side-view thereof, Fig. 3 is a vertical central section through the tube and the attachment, and Figs. 4 and 5 are respectively horizontal sections on line 4—4 and 5—5 of Fig. 1.

Similar reference characters indicate corresponding parts throughout the several figures of the drawing.

Referring to the drawing, and more particularly to Figs. 1 and 2, the collapsible tube is indicated by 10, which collapsible tube has the threaded neck 11. Or, the neck may be made plain, or in any desired shape. The cap 15 is placed upon the neck 11, and closes the tube; removal of the cap permits the removal of the contents of the tube as is well known. This neck with its screw-threads and this cap with the screw-threads engaging therewith, may be of any suitable construction or design, and may be varied as desired.

The collapsible tubes as shown in the drawing and as described are well known in the art and form no part of this invention.

In order to prevent an unequal and irregular discharge of the contents from the tube, my invention provides an attachment which consists of opposed compression members arranged longitudinally to the tube at opposite sides of the same. In the embodiment shown, a strip of heavy cardboard is provided at its middle with an opening 18, by which the strip is slipped upon the neck of the tube, the cap having been first removed. After the attachment is in place the cap is replaced, and holds the attachment securely at that end of the tube. The two free portions 20 and 21 which then depend along opposite sides of the tube are converged in their lower parts to conform to the taper of the tube and united at their lower ends. These ends, when there is a joint between them, may if desired be clenched in with the metal of the tube as shown at 19 in Figs. 2 and 3. As shown in Figs. 4 and 5, they lie at opposite sides of the tube, and are tangential thereto, and parallel to each other, and are of a width greater than the diameter of the tube itself. Their width is approximately the same as that of the tube in its flattened condition after use. In place of cardboard, any other comparatively stiff, yet not entirely inflexible material, may be used for making the attachment.

By this attachment, as is seen in Figs. 1 and 2, the walls of the collapsible tube are protected in an efficient manner, in that any undesired indentation of the tube or unequal pressing thereon is prevented. The compression-members 20, 21, of the attachment, when a desired pressure is exerted thereon, transfer this pressure in an equal and regular manner onto the walls of the tube and onto the material therein, whereby a regular and uniform flow of the contents of the tube is produced through the orifice of the tube. By the pressure of the hand so distributed by means of the walls of this attachment, almost all of the material is forced out of the tube at the part at which pressure is exerted, so that very little material remains therein, and thereby the tube may be gradually, uniformly and regularly emptied of its contents, from the lowermost end of the tube to the upper end thereof,

without any unequal indentation thereof. By this means the unequal indentation is prevented, as for instance often happens when the central portion of the tube is pressed by the user and part of the material is pressed out of the orifice, when the pressure on the contents at that part forces the contents out of the lowermost end of the tube and the overlapping parts thereof, which are intended to remain closed and are intended to prevent the leakage of the tube. Also this prevents the disadvantageous feature which is sometimes the result of certain methods of using these tubes, where the entire tube is taken into the palm of the hand and the contents forced out of the tube; this attachment prevents this manipulation and has a tendency to induce the operative or user to press the lowermost part of the tube first, and then gradually the remaining parts of the tube, until the contents are exhausted therefrom.

A further advantage of my improved attachment is that it enables advertising matter, as shown at 16, to be placed thereon, and especially so when the attachment is made of waterproof material, in which event the advertising matter remains on the walls forming the attachment until the tube is entirely emptied, whereas advertising matter placed directly on the metallic walls forming the tubes is always in contact with the hands when handling the tubes, and this, together with the usual wear and tear thereof, causes the advertising matter to be quickly destroyed or eliminated. The walls of this attachment always remain in their flat condition and afford an excellent means of advertising and display from the beginning of the use of the tube to the completion thereof, and at the same time afford an excellent display when it is desired to offer the tubes for sale on the counters. Placing the ad-

vertising matter upon the attachment described is less expensive, and enables better effects to be produced, than when the same is placed upon the tube itself. 45

A further function of the attachment is that one surface thereof may be used as an addressing card on which the address of the intended consumer is written, and the tube may then be deposited in the mails for transmission to destination. 50

The two parallel walls with one end fastened and one end provided with an opening for the passage of the neck of the container, may readily find application also in connection with small glass vials or bottles, such, for instance, as are used for gold or gilt dust paints, which thereby would act to 60 prevent the breakage thereof, and at the same time as an advertising medium, and also prevent to a certain extent the rolling of the bottles when they are made in cylindrical shape and hold them in position during the use thereof. 65

I claim:

A collapsible tube compressing attachment consisting of a strap provided with an opening adapted to engage the neck of the tube and comprising squeezing members extending downward tangentially in touch with the opposite sides of said tube which collapse toward each other, said squeezing members converging at their lower portions 75 to conform to the tapered lower portion of said tube and being united at their lower ends. 70

In testimony, that I claim the foregoing as my invention, I have signed my name in 80 presence of two subscribing witnesses.

THOMAS C. BOOTH.
